DESIGN FOR A FISH LURE OR SIMILAR ARTICLE

James W. Harvey, Lakeville, Conn.

Application June 6, 1942, Serial No. 107,149

Term of patent 7 years

To all whom it may concern:

Be it known that I, James W. Harvey, a citizen of the United States of America, residing at Lakeville, county of Litchfield, State of Connecticut, have invented a new, original, and ornamental Design for a Fish Lure or Similar Article, of which the following is a specification, reference being had to the accompanying drawing forming part thereof.

Fig. 1 is a plan view of a fish lure embodying my new design.

Fig. 2 is a side view of the same.

Fig. 3 is a head end view of the same.

I claim:

The ornamental design for a fish lure or similar article, substantially as shown.

JAMES W. HARVEY.
